UNITED STATES PATENT OFFICE.

PHILIP F. LACEY, OF CHICAGO, ILLINOIS, ASSIGNOR TO CHICAGO CEMENT VAULT CO.,
NON-INCORPORATED, OF CHICAGO, ILLINOIS, A FIRM COMPOSED OF PHILIP F.
LACEY AND JOHN L. JONISCH.

MOLD.

1,184,756.

Specification of Letters Patent. Patented May 30, 1916.

Application filed December 2, 1914. Serial No. 875,064.

To all whom it may concern:

Be it known that I, PHILIP F. LACEY, a citizen of the United States, and resident of Chicago, in the county of Cook and State of Illinois, have invented certain new and useful Improvements in Molds, of which the following is a full, clear, and exact specification.

This invention relates to improvements in molds, and more especially to those adapted for molding cement burial vaults, the outer side and end walls of which are of sheet metal detachably connected at their meeting ends by means of corner posts of curved or other form for ornamental purposes.

The object of this invention is a simple, effective and durable means, cheap of construction for securing in their operative position the corner posts of a mold, the side and end walls of which are composed of sheet metal, and whereby such corner posts may be easily and quickly locked thereto against accidental detachment, and likewise detached therefrom.

With these ends in view, my invention finds embodiment in certain features of novelty in the construction, combination and arrangement of parts by which the said objects and certain other objects are attained, all as hereinafter fully described with reference to the accompanying drawings, and more particularly pointed out in the claims.

In said drawings: Figure 1 is a bottom plan view of a mold in which my invention finds embodiment. Fig. 2 is a detail longitudinal section of the outer mold. Fig. 3 is a transverse section through both the inner and the outer mold, Figs. 4 and 5 are respectively enlarged elevations of the locking cam. Fig. 6 is an enlarged detail section showing in perspective one of the corner pieces and reinforcing locking bars detached from each other, and Fig. 7 is a perspective view of one of the locking cams.

Similar characters of reference indicate the same parts in the several figures of the drawing.

6—6 indicates the opposing sides and 7—7 the opposing ends of the outer mold, and which for the purpose of lightness and cheapness are preferably composed of sheet metal, which side walls are reinforced at their opposite ends by upright bars 8—8 secured to the outer frame of the side walls by

rivets 9, the end walls 7—7 being likewise reinforced by upright bars 10—10 at their opposite ends secured to the outer faces of the end walls by rivets 11—11.

The bars 8 are longitudinally recessed on their inner face to form a seat 12, and shoulder 13, of which latter and the end of the adjacent side or end 6 or 7, as may be, constitute an abutment for a corner post 14, which as shown in the drawing is rounded, but so far as my invention is concerned may be of any other cross-sectional form.

Integral with, or otherwise fixed to the corner member 14 is a lug 15, projecting through a slot 16 beyond the outer face of the bars 8, and perforated to form a bearing for a pivot 15^a, projecting from an eccentric cam 17, provided with a handle 18, whereby the sides and corner pieces of the mold are quickly attachable and detachable.

It will now be observed that the eccentric cams 17 are in their unlocked position when their handles are elevated as indicated by dotted lines, and are in their locking position when these handles are depressed as shown in full lines.

Spaced apart from the outer member of the mold is the inner member of the mold consisting of opposing side walls 20, end walls 21, and bottom 22, formed of sheet metal and preferably reinforced by a number of longitudinally extending angle irons 23 secured thereto by any means suitable for the purpose, as by rivets or bolts (not shown) and one or more transverse angle bars 24, secured in any suitable manner to the bars reinforcing the inner mold longitudinally.

For strengthening the upper edge of a burial vault and providing a wider base support for the cover, not shown, usually employed in connection therewith, the sheet metal walls of the outer mold are bent outwardly as indicated at 25, as are also the upper ends of the corner posts 14, as indicated at 26, and the reinforcing bars 8 as indicated at 27.

As the mold in which my invention finds embodiment is adapted and intended to be used for molding burial vaults and similar receptacles from liquid cement poured therein, the mold is turned upside down with reference to the article to be molded, and the outer mold projects above the closed bottom of the inner mold, and is open at both ends

as indicated in Fig. 3, with both molds supported around their entire edges by a bed plate 28, which may be of sheet metal in which is formed an upwardly projecting bead 29 for producing in the upper edge of the molded article a corresponding depression adapted to receive a corresponding projection as usual upon the opposing edge of a cover suitable therefor.

10. With the mold in its operative position liquid cement is poured therein until level with the surrounding upper edge of the outer mold, followed by troweling down the upper surface thereof, which is the bottom 15 surface of the molded article, which latter remains in the mold until set, and its walls are hard enough to sustain them when removed from the mold, and which may be quickly done by loosening and then removing 20 the eccentrics from their pivots, followed by first removing the side and end walls, and subsequently the corner posts of the outer mold.

Among the advantages due to my invention 25 may be mentioned that by securing a perforated lug to and projecting it from the corner piece through the sides of a mold, for supporting the locking cam, there is not only provided a positive connection between 30 such a cam and the corner piece, but the strongest and most durable construction for locking a corner piece to the sides of a mold against accidental detachment, and also a construction by which a sectional mold may 35 be assembled in its operation and taken apart in the quickest possible time by workmen more or less unskilled in mechanical devices.

My invention therefore extends to and 40 includes a mold provided with detachable corner sections wherein pivoted locking cams are positively connected with and supported

from the corner piece, and whereby the opposing corner piece and sides of the mold are simultaneously moved toward each other on the locking devices toward a locking position. 45

Having described my invention, what I claim and desire to secure by Letters Patent is:

1. A mold comprising in combination side 50 and end walls, a detachable corner section, locking cams, a pivotal support therefor projecting from the corner section through said side and end walls.

2. A mold comprising in combination reinforced sheet metal side and end walls, a detachable corner section for the mold, a perforated lug fixed to the corner piece projecting through the reinforcement for said walls, and locking cams detachably pivoted in said 60 lug.

3. A mold comprising in combination opposing side and end walls, and separate corner pieces, reinforcing bars respectively at the opposite ends of said walls, provided 65 with a recess upon their inner face forming an abutment for the corner pieces, perforated lugs projecting from the corner pieces through the reinforcing bars, and locking cams removably sleeved in said lugs, adapted 70 to engage the reinforcing bar whereby the corner sections and the side walls of the mold are simultaneously moved toward each other, and detachably locked in their operative position. 75

In witness whereof, I have hereunto set my hand and affixed my seal this 28th day of November, A. D. 1914.

PHILIP F. LACEY. [L. S.]

JNO. G. ELLIOTT,
MILDRED ELSNER.

Copies of this patent may be obtained for five cents each, by addressing the "Commissioner of Patents, Washington, D. C."

It is hereby certified that in Letters Patent No. 1,184,756, granted May 30, 1916, upon the application of Philip F. Lacey, of Chicago, Illinois, for an improvement in "Molds," the name of the second-mentioned partner of the assignee firm was erroneously written and printed as "John L. Jonisch," whereas said name should have been written and printed as *John L. Janisch*, as shown by the records of assignments in this Office; and that the said Letters Patent should be read with this correction therein that the same may conform to the record of the case in the Patent Office.

Signed and sealed this 25th day of July, A. D., 1916.

[SEAL.]

F. W. H. CLAY,

Acting Commissioner of Patents.
